CRIMPING MACHINE

Otto Ganio, New York, N. Y.

Application September 12, 1935, Serial No. 40,316

9 Claims. (Cl. 154—30)

This invention relates to crimping machines and more particularly to a device to crimp the petals of artificial flowers.

The main object of the invention is to provide 5 a machine to form the petals of an artificial flower with a series of undulations similar to the undulations appearing on the petals of a real flower.

A further object of the invention is to provide 10 a bed plate with a series of corrugations on its top face and a presser arm having similar corrugations for crimping a blank sheet of material.

A further object of the invention is to provide 15 a roller having a series of corrugations on its periphery to give the crimped material a permanent set.

A further object of the invention is to construct 20 a device of this kind having means to bend the material from which the artificial flowers are made in regular undulations and means to give the bent material a permanent set.

With the above and other objects in view, as 25 will be presently apparent, the invention consists of certain novel details of construction and combinations of parts hereinafter fully described, illustrated in the accompanying drawings and specifically claimed.

Figure 1 is a side view of the crimping machine showing the presser arm in an opened position.

Figure 2 is a similar view as Figure 1 but showing the presser arm in a closed position.

Figure 3 is a top view of the machine.

Figure 4 is a top view of the bed of the machine.

Figure 5 is a front view of the bed plate.

Figure 6 is a rear view of the bed plate.

Figure 7 is a top view of the presser arm.

Figure 8 is a bottom view of the presser arm.

Figure 9 is a sectional detail showing the presser arm in contact with the bed of the machine with a portion of the flower petal between the two elements.

Figure 10 is a view of the roller.

Figure 11 is a view of the flower partly crimped.

Referring now to the drawings in detail, numeral 1 designates the stand of the machine, 2 the bed plate fastened thereto and 3 the presser arm. Pivoted to the sides of the bed plate is a forked lever 4 for actuating the presser arm and the roller 5.

The bed plate comprises a hollow member having a curved top 6 formed with a series of corrugations 7. The presser arm 3 is curved at

the forward end 8 to correspond to the curvature of the top of the bed plate and the underside of the said arm is also provided with corrugations 9 to match the corrugations formed in the bed plate. The rear of the arm is offset as at 10 and 5 furnished with two bearing members 11 in which is journalled the roller 5 having a set of corrugations 12 on its periphery corresponding to the corrugations formed in the bed plate. A pin 13 is embedded in the offset portion of the arm with 10 its ends projecting in the elongated slots 14 of the lever 4. A spring 15 is interposed between the forked portion 16 of the lever and the raised portion 17 of the presser arm for a purpose to be later described. Bosses 19 and 20 are provided 15 on the raised portion 18 of the arm and the forked portion 16 of the lever to properly position the spring. At both ends of the spring are asbestos washers 21 and 22 in order to heat insulate the handle member 23 from the rest of 20 the structure. Within the interior of the bed plate can be placed a heating element such as a gas burner or any other source of heat to keep the device at constant relatively high temperature.

In operation a blank piece of material A is cut in the segmental form shown in Figure 11. Each segment represents a petal of a flower. The segments of material are then consecutively placed on the bed plate 2 and the lever 4 moved 30 to the left. This will cause the roller 5 to ride on the top of the bed plate as shown in Figure 2 and swing the presser arm against the bed plate and emboss the material to correspond to the corrugations formed in the bed plate and presser 35 arm. The spring 15 bearing on the presser arm will supply sufficient pressure to form the corrugations B in the segments A. As the presser arm moves to the left the petals will in addition wrinkle as at C at right angles to the corrugations B.

Numerical 26 designates a stop to regulate the anti-clockwise movement of the lever and 27 the stop for the clockwise movement.

It will thus be seen that I have provided a 45 simple, efficient and practical device for the purpose specified. It is obvious that changes may be made in the form and construction of the invention without departing from the principles 50 involved therein. It is not, therefore, desired to confine the invention to the exact form herein shown and described but it is desired to include all such as come within the scope of the appended claims.

Having described my invention, I claim:

1. In a device of the class described, a bed plate, the upper face of said bed plate being curved and provided with corrugations, a presser arm provided with corrugations to match the corrugations of the bed plate adapted to close on said bed plate and to slide therealong in the direction of said corrugations, a roller journalled at the rear end of said presser arm, said roller tracking after the presser arm to engage said bed plate provided on its periphery with corrugations to match the corrugations on said bed plate, and a lever pivoted to said bed plate for actuating said presser arm. 5
- 10 2. In a device of the class described, a bed plate, the upper face of said bed plate being curved and provided with corrugations, a curved presser arm provided with corrugations to match the corrugations of the bed plate, and adapted to close on said bed plate, and a forked lever pivoted to the sides of said bed plate for actuating said presser arm, said presser arm provided with a pivot, the ends of said pivot entering slots formed in said lever. 15
- 15 3. In a device of the class described, a bed plate, the upper face of said bed plate being curved and provided with corrugations, a curved presser arm provided with corrugations and adapted to close on said bed plate and to slide therealong in the direction of said corrugations, a roller journalled at the rear end of said presser arm, said roller tracking after the presser arm to engage said bed plate provided on its periphery with corrugations to match the corrugations on said bed plate, and a forked lever pivoted to the sides of said bed plate for actuating said presser arm, said presser arm provided with a pivot, the ends of said pivot entering slots formed in said lever. 20
- 20 4. In a device of the class described, a bed plate, the upper face of said bed plate being curved and provided with corrugations, a curved presser arm provided with corrugations and adapted to close on said bed plate and to slide therealong in the direction of said corrugations, a roller journalled at the rear end of said presser arm tracking after the presser arm to engage said bed plate provided on its periphery with corrugations to match the corrugations in said bed plate. 25
- 25 5. In a device of the class described, a bed plate, the upper face of said bed plate being curved and provided with corrugations, a curved presser arm provided with corrugations and adapted to close on said bed plate and to slide therealong in the direction of said corrugations, a roller journalled at the rear end of said presser arm tracking after the presser arm to engage said bed plate provided on its periphery with corrugations to match the corrugations in said bed plate. 30
- 30 6. In a device of the class described, a hollow bed plate, the top face of said bed plate being curved and provided with longitudinal corrugations, a U-shaped lever pivoted to the sides of said bed plate, a presser arm pivoted to said lever, the forward end of said presser arm being curved and provided on its bottom face with corrugations 35 to match the corrugations of the said bed plate, the rear of said presser arm being offset from the forward portion thereof and provided with outwardly extending portions, a roller journalled in said outwardly extending portions, said roller having a set of corrugations on its periphery to match the corrugations formed in the bed plate, a compression spring between the crotch of the said lever and the said offset portion of the presser arm, and a set of stops for limiting the clockwise 40 and anti-clockwise movement of said lever.
- 35 7. In a device of the class described, a bed plate, a presser arm, a lever pivoted to said bed plate, said presser arm having a pivotal connection with said lever to close upon said bed plate, a roller at the rear end of said presser arm, said roller tracking after the presser arm and adapted to be engaged by said bed plate to rock said presser arm upon said pivotal connection to close said presser arm upon said bed plate. 45
- 40 8. In a device of the class described, a bed plate, a presser arm adapted to close on said bed plate, the underface of said arm provided with longitudinal corrugations, and a roller journalled at one end of said arm tracking after said presser arm in engagement with said bed plate. 50
- 45 9. In a device of the class described, a bed plate, a curved presser arm adapted to close on said bed plate, the underface of said arm provided with longitudinal corrugations, one end of said presser arm being offset from the rest of said arm, and a roller journalled in said offset portion tracking after said arm in engagement with said bed plate.

OTTO GANIO. 55
